UNITED STATES PATENT OFFICE.

THOMAS H. LOGAN, OF THE UNITED STATES ARMY.

ARTESIAN-WELL BORER.

SPECIFICATION forming part of Letters Patent No. 444,839, dated January 20, 1891.

Application filed March 15, 1890. Serial No. 344,040 1/2. (No model.)

To all whom it may concern:

Be it known that I, THOMAS H. LOGAN, of the United States Army, at present stationed at Fort Hancock, in the county of El Paso 5 and State of Texas, have invented a new and Improved Artesian-Well Borer, of which the following is a full, clear, and exact description.

This invention relates to earth or rock 10 augers of the class employed in boring Artesian wells, the object of the invention being to provide an efficient, simple, and durable auger or borer, and one which will be actuated by the weight of the connecting-rods 15 and sink wells in rock, gravel, earth, or sand without the use of water.

To the ends above named the invention consists of certain novel constructions, arrangements, and combinations of elements 20 which will be hereinafter fully described, and specifically pointed out in the claims.

Reference is to be had to the accompanying drawings, forming a part of this specification, in which similar figures and letters of reference indicate corresponding parts in all the 25 views.

Figure 1 is a side view in partial section of my improved Artesian-well borer, parts being broken away. Fig. 2 is a central vertical sectional view taken from the direction of the arrow *a*, shown in connection with Fig. 1. Fig. 3 is a detail view upon an enlarged scale of the cap of the main tube. Fig. 4 is a sectional view on line 4 4 of Fig. 5. Fig. 5 is an 30 enlarged vertical sectional view of the upper portion of the main tube and its connections. Fig. 6 is a cross-sectional view on line 6 6 of Fig. 7. Fig. 7 is an enlarged sectional detail view of the lower portion of the main tube 35 and its connections. Fig. 8 is a plan view of the tool employed in boring rock, and Fig. 9 is a side elevation thereof.

In the drawings, 10 represents the main tube of the borer, which tube is by preference made in sections *b* and *c*, that are united by an internal sleeve 11. Within the tube 10 I arrange a tube 12, that is held in the section *c* by the sleeve 11 and by a collar 14, held in place just within the lower end of the 40 tube 10. This inner tube 12 has a number of inwardly-extending projections 15, that fit within the spiral grooves *d*, formed in a pro-

jection 16, that extends down from the rod-coupling shank 17, said shank proper being squared or irregularly formed to receive a 55 wedge-shaped collar or sleeve 18, the upper end of the shank being threaded to engage the stock of a coupling-eye 19. To the upper end of the tube 10 I secure a cap 20. Within the top of this cap 20 there is arranged an 60 apertured partition 21, which carries plates 22, said plates being centrally apertured and formed with slots *e*, through which there extend studs or pins *f*, that are carried by the partition 21. The plates 22 each carry a pivotally-mounted dog 23, having serrated edges 65 *g*, said dogs being arranged so that they may be extended outward through slots *h*, that are formed in the cap-walls. This construction is provided so that when the shank 17 is 70 lowered to the position in which it is shown in Figs. 1 and 2 the wedge-shaped collar 18 will bear upon the plates 22 and the dogs will be moved outward to a position such that their edges *g* will bear against the well-casing 75 and hold the tube 10 against any rotary motion.

A portion of one side of the lower end of the tube 12 is cut away to provide for the mounting of a hooked pawl 25, which said pawl engages a ratchet 26, formed at the upper end of the stock 27, the stock being held against any upward motion by a diaphragm or partition 28, arranged within the tube 12, and against any downward motion by an internal collar 29, that is carried by the tube 12. 80

To steady and guide the stock I provide the collar 14 with a bearing-collar 30, which abuts closely against the peripheral face of the stock, all undue play being prevented by a 85 collar 31, that is carried by the stock, the collar being held to place upon the stock by a set-screw 32, which screw may be turned inward so that it will bear against the shank 33 of an auger 34.

In order that the earth or cuttings gathered by the auger 34 may be housed and raised from the bore made by the auger, I provide a casing 40, that fits about the tube 10, the upper end of the casing being formed with an 90 inwardly-extending flange 41, that overlaps an annular shoulder 42, formed at the lower end of the said tube 10, all upward movement of the casing at times when the instrument is 95 100

being lowered to working position being prevented by springs 43, that are arranged to bear upon the upper face of the flange 41.

From the construction above described it will be seen that if the instrument be lowered to working position the wedge-shaped sleeve 18 will act to force the dogs 23 outward, so that they will bear against the well-casing and act to hold the tube 10 and the parts rigidly connected thereto against all rotary movement. Then if the coupling-rods be raised the shank 17, and with it the extension 16, will be carried upward and the pawl 25 will slip on its ratchet 26, after which if the support of the coupling-rods be released their weight will act to return the shank 17 to the position in which it is shown in Fig. 2, and in so returning the tube 12 will be revolved, and in revolving will carry the stock forward, so the stock-ratchet at this time being engaged by the pawl 25, so that a forward movement will be imparted to the auger.

It will be noticed that the auger-bits 46 extend outward slightly beyond the peripheral edge of the casing 40, so that as the auger operates a hole of sufficient diameter to permit of the downward passage of such casing will be formed.

After sufficient earth or cuttings to fill the casing has been gathered the implement is drawn to the surface and the contents of the casing discharged.

In boring rock the tool shown in Figs. 8 and 9 is employed. Said tool consists of a suitable head 50, provided with a shank 51, for connection with the stock 27. The head 50 is provided with a number of downwardly-projecting cutters 52 53, said cutters in the present instance being six in number, arranged as shown, three on each side of the center of the head. At or near the periphery of the head 50 another set of cutters 54 is pivotally secured to hang vertically when the head is raised. The said cutters 54 are preferably two in number, arranged diametrically opposite each other. All the cutters 52 53 54 have suitable angular cutting points.

In operation, when the head is lowered into operative position the weight of the machine and the impact of the blow causes the six cutters 52 53 to penetrate the rock and the two pivoted cutters to project beyond the head to the wall of the boring. The head makes two complete revolutions and cuts the side and bottom of the hole, thereby when working below a well-casing cutting a hole a trifle larger than the outer diameter of said casing.

Having thus described my invention, I claim as new and desire to secure by Letters Patent—

1. In an earth or rock auger, the combination, with a tube and a shank reciprocating in said tube and adapted to operate the auger, of dogs adapted to be projected through the tube by the reciprocation of the shank to engage the well-casing and hold the said tube from rotary movement, substantially as described.

2. In an earth or rock auger, the combination, with a tube and a reciprocating shank provided with a wedge-shaped collar and adapted to operate the auger, of horizontal plates held to slide in the tube and engaged by said collar, and dogs carried by said plates, substantially as herein shown and described.

3. In an earth or rock auger, the combination, with an outer tube and means for preventing it from rotating, of an inner tube provided with inwardly-extending projections at its upper end, a tool-stock in the lower end of the inner tube, a reciprocating shank having a spiral extension, with which the projections of the tube engage and by which the said tube is rotated, and means for imparting the rotary movement of the tube to the tool-stock, substantially as and for the purpose set forth.

4. In an earth or rock auger, the combination, with the outer tube 10, the reciprocating shank 17, provided with the spiral extension 16, and means for preventing the tube from turning, of the inner tube 12, provided with the inwardly-extending projections 15 at its upper end and with the pawl 25 at its lower end, and the tool-stock 27, mounted to turn in the lower end of the tube 12 and provided with the ratchet 26, with which the pawl 25 engages, substantially as herein shown and described.

5. In an earth or rock auger or borer, the combination, with an inclosing tube, of a cap carried thereby and formed with slots in its peripheral face, and a partition 21, plates 22, held to slide upon the partition, dogs 23, pivotally connected to the plates 22 and formed with serrated edges, a rod-coupling shank formed with a spirally-grooved projection, a wedge-shaped sleeve 18, through which the shank passes, such sleeve being arranged to bear upon the plates 22, a tube 12, formed with projections 15, which enter the spiral groove of the rod-coupling-shank projection, a stock formed with a ratchet 26, a pawl carried by the tube 12 and arranged to engage said ratchet, and an inclosing casing 40, substantially as described.
